(74) *Attorney, Agent, or Firm*—Heslin Rothenberg Farley & Mesiti P.C.

(57) **CLAIM**

The ornamental design for the lighting fixture, as shown and described.

DESCRIPTION

FIG. 1 is a perspective view of a lighting fixture in accordance with the new design;

FIG. 2 is a front elevational view thereof, a rear elevational view being a mirror image thereof;

FIG. 3 is a right side elevational view thereof, a left side elevational view being a mirror image thereof;

FIG. 4 is a bottom view thereof; and,

FIG. 5 is a perspective view of an alternative embodiment of a lighting fixture in accordance with the new design a portion of which is cutaway to illustrate indeterminate length.

The broken lines in the drawings are for illustrative purposes only and form no part of the claimed design.
